Primary Examiner—A. Hugo Word*Assistant Examiner*—Doris V. Coles*Attorney, Agent, or Firm*—Terry M. Gernstein[57] **CLAIM**

The ornamental design for a fishing rod holder, as shown and described.

DESCRIPTION

FIG. 1 is a front, top and side perspective view of the fishing rod holder showing my new design;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom plan view thereof.

Part of claimed design in FIGS. 2-5 has been broken away for the convenience of illustration.

FIG.1

FIG. 3

FIG. 2

FIG. 4

FIG. 5

FIG. 6

FIG. 7
